United States Patent Office

Des. 181,014
Patented Sept. 17, 1957

181,014

TRANSPARENCY VIEWER OR SIMILAR ARTICLE

Clarence B. Mitchell, Chicago, Ill., assignor to Optics Manufacturing Corporation, Philadelphia, Pa., a corporation of Illinois

Application April 19, 1957, Serial No. 45,805

Term of patent 14 years

(Cl. D61—1)

FIG. 1

FIG. 3

FIG. 4

FIG. 2

FIG. 5

FIG. 6

FIG. 7

Fig. 1 is a front perspective view of a transparency viewer or similar article showing my new design;

Fig. 2 is a rear perspective view;

Fig. 3 is a side elevational view to a reduced scale, the opposite side having substantially the same appearance;

Fig. 4 is a front elevational view, to a reduced scale;

Fig. 5 is a top plan view to a reduced scale;

Fig. 6 is a rear elevational view; and

Fig. 7 is a bottom plan view thereof.

A portion of the drawing figures is diagonally lined to indicate transparency.

I claim:

The ornamental design for a transparency viewer or similar article, as shown and described.
